MINING OF SULPHUR.

Application filed April 21, 1926. Serial No. 103,420.

This invention relates to the mining of sulphur, and has for its object the provision of certain improvements in the mining of sulphur by underground fusion.

- 5 In the mining of sulphur by underground fusion, in accordance with the so-called Frasch process, a hole or well is drilled through the overlying strata to the bottom of the sulphur formation, which hole is usually 10 cased with an eight inch or ten inch pipe, and then, through a system of concentric pipes properly arranged within this casing, superheated water is pumped down near the foot of the hole or well where it is discharged 15 into the sulphur formation and melts the sulphur. The melted and liquid sulphur enters one of the concentric pipes, usually through a strainer, and is raised to the surface of the ground, generally by means of an air lift. 20 The well continues to operate and produce sulphur until the sulphur-bearing formation is locally exhausted or until the piping equipment is broken by subsidence of the ground due to the extraction of the sulphur content. 25 The underground sulphur formation is usually found in the form of so-called domes, at depths varying around 500 to 1500 feet below the surface of the ground. These sulphur domes are usually immediately overlaid by a 30 cap rock formation of porous limestone, which in turn is overlaid by strata of gumbo, quicksand, sand, gravel, and clay. Beneath the sulphur formation is usually found a layer of gypsum or anhydrite and layers or domes 35 of salt.

The sulphur formation itself usually consists of an extremely porous or reticulated rock with the interstitial spaces filled with sulphur. The sulphur formation often contains an amount of water, forming what might be considered an underground lake of brine or salt water containing, for example, 4800 grains per gallon of solids in solution, mainly, sodium chloride, and in addition hydrogen sulfide and other soluble sulfides.

In the so-called Frasch system of mining sulphur by underground fusion, hot water is the vehicle commonly used for conveying and transmitting heat to the sulphur. Inasmuch as 40 sulphur melts at a temperature around 240° F., which is above the boiling point of water at atmospheric pressure, the heating water is highly superheated, and is pumped into the sulphur deposit under a high pressure. The 45 temperature to which the water can be super-

heated, is, however, limited by the danger of overheating the sulphur, in which case it becomes viscous. Accordingly, the water is heated to a temperature that avoids overheating of the sulphur, but which is sufficient 60 to bring about effective melting thereof as the highly heated water comes in contact with the underground sulphur. The sulphur thus melted flows to the lowest part of the deposit 65 and surrounds the sulphur-withdrawing pipe, whence it is elevated, usually by means of an air lift, to the surface of the ground. The water introduced may consequently be heated under pressure to about 320° F. and pumped 70 into the sulphur deposit, this water replacing the sulphur removed by the well, together with water already contained in the deposit, which may be withdrawn by means of bleed-wells, situated at suitable points in the deposit. The bleed-wells are usually located so 75 as to withdraw the cold water or salt water from the lower part of the sulphur formation.

The sulphur dome may underlie a considerable surface area of ground. The dome may, for example, be as much as a mile in diameter and the underground lake forming a part of the deposit or adjacent thereto may contain billions of gallons of underground water or 80 brine.

In the mining of sulphur in an underground sulphur deposit one or several wells are usually drilled and operated at one part of the deposit until the sulphur-bearing formation is exhausted locally and then other 85 wells are drilled at another part of the deposit, and the deposit is progressively worked in this way until exhausted. The operation of a sulphur mine in this way is an operation of large magnitude. The amount of highly 90 heated water that it is necessary to pump into a deposit in a single day may amount to several million gallons in commercial operations.

The pumping of a large amount of super-heated water into the deposit results in the gradual accumulation of a progressively increasing amount of hot water in the deposit. The specific gravity of the original deposit water is, for example, about 1.08 and the 105 temperature, for example, about 108° F.; while the specific gravity of the clean hot water pumped into the mine is in the neighborhood of 0.91. Owing to this difference in specific gravity, the hot water rises or 110

- tends to rise to the top of the dome, displacing the cold water downward and while there is some diffusion and mixing, in a general way the water at the top of the dome becomes cleaner with only a small amount of solids in solution, while the water in the lower part of the deposit contains about its original content of dissolved solids until displaced by the cleaner water from above.
- 10 The continued supply of a large amount of highly heated water to the mine forms one of the major expenses of the operation, this water being commonly obtained from a source several miles distant from the mine at a temperature around, for example, 68° F., and being heated to a temperature around 324° F., before it is pumped into the mine. Of the total heat supplied to the water, only a small part is available for melting the sulphur. Thus, in heating the water from 68° F. to 324° F., 256 B. t. u.'s are supplied by the combustion of fuel to each pound of water which is pumped into the deposit. Since sulphur melts at around 240° F., the only effective heat supplied to the water is that between the maximum temperature of the water and the melting point of sulphur, for example, around 85 B. t. u.'s of the total of 256 B. t. u.'s supplied to the water.
- 15 30 My present invention broadly involves maintaining a predetermined pressure of the body of hot water accumulating in the underground sulphur deposit. In another aspect, the invention contemplates a balancing of the underground pressures in the sulphur deposit whereby the pressure of the hot water accumulating in the deposit is maintained approximately equivalent to the normal hydrostatic head or pressure of water at this level. This I accomplish by a regulated withdrawal of cold water from the lower part of the deposit together with the withdrawal of regulated amounts of hot water from the upper part of the deposit. The withdrawal of this hot and cold water is so correlated with the introduction of superheated liquid into the deposit as to maintain a predetermined pressure of the body of hot water in the upper part of the deposit. Preferably, this predetermined pressure is substantially the normal hydrostatic head or pressure of water at the level of the deposit where the hot water accumulates. The hot water withdrawn from the deposit is reintroduced into the deposit, with or without purification and/or further heating, preferably at a well zone remote from the zone of withdrawal.
- 20 35 40 45 50 55 60 65 70 75 80 85 90 95 100 105 110 115 120 125 130 Throughout the specification and the appended claims "cold water" withdrawn from the deposit is to be understood as water or brine at a temperature well below the melting temperature of sulphur, and "hot water", withdrawn from the deposit is to be understood as water or brine at a temperature

slightly above or slightly below the melting temperature of sulphur, and varying in practice from about 200° C. to about 300° C.

The present invention is of particular advantage in the mining of sulphur from deposits which have been operated for a considerable time until there has accumulated a large amount of hot water in the upper portion of the dome or formation from which the sulphur has been exhausted. After long periods of operation, the temperature of this hot water, accumulating in the upper portion of the dome, will be considerably above the melting point of sulphur, which is about 240° F., and the temperature of this water may be as high as 300° F., or even higher. This hot water is contained under considerable pressure, usually in excess of the normal hydrostatic pressure or head of water at that level. The pressure of this hot water may develop to a considerable magnitude unless means are taken to control it, or unless it is relieved by a natural or artificial outlet for the hot water.

The path of the hot water introduced into the sulphur deposit is towards the highest point, due to the difference in specific gravity between the fresh hot water and the cold brine with which the deposit is filled. If the overlying stratum above the porous cap rock are impervious to water, the accumulation of hot water at the high point becomes greater and greater, and is only subject to heat loss through radiation. The situation is somewhat different, however, if the material above the cap rock is a sand or gravel, or if there is any channel between the hot water pool and porous strata higher up in series above the cap rock. If a channel is opened into any such upper layer the escape of hot water is easy.

105 During the mining of sulphur by underground fusion, it is necessary to pump superheated water under pressure into the deposit, and unless an equivalent amount of the original brine is drawn off through bleed-wells or can flow off through porous strata, the pressure in the deposit starts to build up and eventually becomes so great that there is danger of it forcing a way to the surface, and when pressure on this water (which is at a temperature above 212° F.) is released, a portion of it will vaporize and an explosion comparable to a boiler explosion can result.

110 It is the practice in mining sulphur from deposits where there is an impervious capping to drill bleed-wells into the lower and colder portion of the deposit and use these bleed-wells to relieve the pressure. The pressure in the deposit necessary to force the water or brine out through these bleed-wells depends, of course, upon their size and number, but there may also be a considerable pressure above the hydrostatic head on the hot water accumulation at the top of the deposit. This will be due to the greater specific gravity of

the cold brine in the deposit which is bled off, and also to the velocity and friction heads which must be overcome in the bleed-wells. For instance, it is very difficult to keep the 5 surface pressure above the top portion of the deposit down to as low as 10 pounds per square inch from wells having the same discharge elevation as the bleed-wells.

The hot water is introduced and the sulphur taken out through a series of drill holes 10 or wells. After a certain time of operation these wells fail, generally from breaking of the equipment due to ground movement and also from corrosion and other causes. The 15 well then has to be abandoned and it is generally impossible to recover any considerable portion of the casing or equipment which was in the hole, and in many cases impossible to plug the hole at any considerable depth. 20 Even if the stratum directly above the cap rock are impervious, such as for instance, a heavy clay, there are always a number of sand strata in the sediments overlying these sulphur domes. It is quite probable that broken 25 drill hole casings extending into the cap rock may give a communication between the hot water zone in the cap rock and porous strata in the overlying sediments. If there is a 30 pressure at the surface, of a few pounds per square inch, this pressure can, of course, force the hot water from the heated water zone through such channels of communication as broken pipes or cracks through any overlying strata into porous strata where the hot water 35 can run off laterally even to considerable distances and the heat units contained in it will be lost.

There seems to be no doubt that this 40 condition has existed at various times in the mining of sulphur by underground fusion. In one case it is stated that for several years there was not sufficient pressure in the deposit to return any bleed water, all of the 45 fresh water, which was introduced in large quantities into the deposit, flowing off laterally through porous sand beds.

I have discovered that these operating difficulties can be ameliorated by a balancing of the 50 underground pressures in accordance with the principles of my present invention. Thus, the pressure at the bleed-wells may be reduced so as to maintain a pressure over the hot water pool, at the top of the deposit, approximately equivalent to the normal hydrostatic pressure or head on the deposit. There 55 is then little tendency for either a flowing out of the hot water into porous strata or a flowing in of cold water from such porous strata into the deposit; this latter condition 60 being otherwise possible where the pressure on the hot water in the deposit is lower than the normal hydrostatic head. Where this condition of balanced pressure is approximately maintained, there will be little loss of 65 heat, excepting through radiation, from the

hot water pool or reservoir, and this reservoir will increase in size or the heat from it can be reused as desired, both of which materially assist in the mining of sulphur by underground fusion.

The pumping of bleed wells for the purpose of balancing or equalizing pressures may be done by air lifts or more economically by the use of standard pumping equipment, such as sucker rod pumps or centrifugal 70 pumps. Generally, there is sufficient hydrogen sulfide dissolved in the original deposit water so that the use of a centrifugal pump at the outlet of a bleed-well is impractical on account of the release of hydrogen sulfide gas 80 and the stopping of liquid flow through the pump from accumulation of such gas in the suction line. This can be readily overcome by the use of a deep-well centrifugal pump, placing the pump in the hole several feet below the surface and sufficiently deep so that the gas dissolved in the water will not be released under the pressure existing on the suction side of the pump.

The balancing of underground pressure 90 may also be of great advantage in the mining of sulphur deposits where there is a pervious layer just above the cap rock. This pervious layer may be sealed by a heavy mud pumped into the porous cap rock. This mud will work 95 its way into the interstices of the pervious layer of sand and eventually form a seal that will be thoroughly effective in holding back the hot water below it, providing the pressure of this water is not allowed to exceed 100 to any considerable extent the natural hydrostatic head of the deposit. This result is accomplished by regulating the withdrawal of cold brine through the bleed wells and may be assisted by the withdrawal of hot water 105 from the hot water zone.

The invention will be further described in connection with the accompanying drawing, which illustrates in a conventional and graphic manner a section of a sulphur mine 110 and apparatus embodying the invention and adapted for the practice of the improvements of the invention. The showing is largely conventional and various parts are relatively magnified and the horizontal dimensions of 115 the pipe and of various parts are relatively magnified for convenience of illustration.

In such a mine as represented in the accompanying drawing, the sulphur deposit is 120 usually overlaid by a cap rock of limestone, above which are strata of gumbo, quicksand, sand, gravel and clay. Below the sulphur deposit there are usually bodies of gypsum and salt. In the drawing, there is represented a region marked "Hot water zone" from 125 which it is assumed the sulphur has been melted and removed, and which is assumed to be full of hot water accumulated from the mining operation. The hot water will also extend upwardly into the porous cap rock. 130

It will be apparent that as the sulphur is melted and withdrawn, the space originally occupied by the sulphur must be filled either by the subsidence of the earth above or by the hot water pumped into the mine. It will also be understood, as above explained, that the hot water which is pumped into the mine, where the active mining operation is going on, is lighter than the cold salt water originally contained in the mine, so that the fresh hot water tends to rise and accumulate in the upper levels of the dome.

In the drawing, one of a series of active sulphur wells is indicated at 1, this well being made up as usual of a series of concentric pipes with a casing. For convenience of illustration, the entire series of pipes is omitted and only two concentric pipes are shown, the inner pipe 3 being intended to illustrate graphically the pipe through which the molten sulphur is pumped from the mine and which extends to the bottom of the deposit, and the outer casing 2 illustrating the outer pipe within which the hot water is pumped down into the mine.

A bleed-well 5 is shown as located at a distance from the active sulphur wells and as leading from a lower level of the deposit from which the colder water may be withdrawn in regulated amounts. A well 6 is shown as located so as to withdraw water from the top of the dome. This well extends down into the porous cap rock and at its upper end is enlarged so as to accommodate a suitable pump, shown as a centrifugal pump 8 driven by a motor 9 and having an extension 10 extending down in the hot water zone and which may terminate in a perforated end 11 through which the hot water is admitted into the pipe 10 and thence into the centrifugal pump 8. The well pump 8 may be of any suitable construction for keeping the water under pressure so that no expansion or freeing of steam can take place near or at the surface of the ground. A heavy duty centrifugal pump such as a multi-stage centrifugal pump can be used. This pump should be located at a sufficient distance below the surface of the ground to receive the hot water before its pressure has been reduced sufficiently to permit vaporization and cooling thereby. The pump may be located, for example, from 60 to 100 feet below the surface of the ground or it may be located at an even lower level if desired.

The water pumped from the well 6 passes through pipe 13 to the well 1 where it is again forced down into the deposit. A pump 17 is provided which may supplement the centrifugal pump 8, but with a suitable centrifugal pump, the pump 17 may be omitted, or it may be used only for supplementing the centrifugal pump as occasion may arise for doing so.

65 The well 5 is illustrated as extending into

the sulphur-bearing strata and to a point below the point at which the sulphur is withdrawn by well 1. A pump 12 is shown as located within the casing of well 5 driven by a motor 14. The pump 12 may either be a centrifugal or a common sucker rod pump. If the pump 12 is a centrifugal pump, it is located a sufficient distance below the surface of the ground so that the dissolved gases will not be released by reduced pressure on the suction side and thus stop its use. If the pump 12 is of the sucker rod type, the rod will be longer than illustrated in the drawing so as to carry the pumping mechanism lower in the well and nearer to the water level of the deposit.

An old well casing which has been broken and abandoned by subsidence of the ground is represented at 15 on the drawing. The porous cap rock is shown as distorted as well as the layer of porous sand and gravel and the rupture of the pipe is exaggerated so as to graphically illustrate the communication which might be attained by means of the broken well casing between the hot water zone and the porous gravel.

At 16, on the drawing, is illustrated a rupture of the porous cap rock and the thin layer of impervious clay immediately above it so as to form an avenue of communication between the hot water zone and a porous sand or gravel stratum.

An illustration is not given in the drawing of a case where the pervious stratum of gravel directly overlies the porous cap rock, and it is considered that it will not be necessary to illustrate this point, nor will it be necessary to illustrate an extra well which might be used to force mud into such a pervious stratum in order to seal it against admission of hot water from the hot water zone.

In the pending applications of Robert H. Stewart, Serial No. 699,448 and Serial No. 95,542, there are described certain methods of withdrawing hot water from the hot water zone as it accumulates in the mining of sulphur by underground fusion. My present invention aims to maintain this zone of hot water in the mine and to prevent it from flowing away through porous underground strata. The invention more specifically aims to maintain a pressure or head of hot water in the hot water zone, approximately equivalent to the hydrostatic head of water at this level.

At the beginning of the mining operations of the dome, the sulphur wells are conveniently located near the top of the dome, near the location of well 6 in the drawing, and such wells are operated until the sulphur is exhausted at that location. Usually at the beginning such wells are operated independently of any other wells such as for instance, bleed-wells. These wells are operated until the sulphur is exhausted at that location or

until the subsidence of the ground causes breaking of the piping equipment. As the deposit surrounding the first wells becomes exhausted, additional wells are drilled at a distance from the first wells. These wells may be at a location such as illustrated by the wells 1 or 15 in the drawing and the well 6 may then be an exhausted sulphur well which is used merely for the purpose of withdrawing the hot water from the upper part of the deposit. As the mining progresses the accumulation of hot water in the upper part of the deposit becomes greater, and often it is necessary to either lower the level of this hot water zone to melt more sulphur, or to build up an accumulation of hot water so that it will extend low enough in the deposit to melt more sulphur.

It is at this stage of the mining operation that the operation of the bleed-wells, the hot water with-drawing wells, and the hot water introducing wells may be so carried on that, with the accumulation of a large reservoir of hot water, such high pressures may build up as to cause this hot water to either rise to the surface of the ground or flow away underground.

The present invention aims to prevent this objectionable condition by maintaining a predetermined pressure in the accumulated reservoir or underground pool of hot water. To this end, pumps are preferably located in the bleed-wells to supplement and increase the withdrawal of water from these wells so that the pressure as indicated in pipe 13 will only be slightly above the normal hydrostatic pressure of the mine.

In effect, I am dealing with three factors that influence the pressure of the accumulated reservoir or underground pool of hot water, viz: (1) the introduction into the deposit of superheated liquid, (2) the withdrawal from the deposit of relatively cold water, and (3) the withdrawal from the deposit of hot water. In accordance with my present invention, these three factors are regulated and correlated so as to maintain the desired predetermined pressure of the accumulated pool of hot water in the upper portion of the deposit. In other words, the introduction into the deposit of superheated water and the withdrawal of both hot and cold water from the deposit are controlled and regulated so as to maintain the desired predetermined pressure of the accumulated pool of hot water.

The practice of the invention brings about a pronounced conservation of heat or hot water in the mining of sulphur by underground fusion. Decreased fuel consumption, as well as increased fuel efficiency, required for supplying heat to the water introduced into the sulphur deposit, are attained, and in general there results an important all-around economy.

The present invention, by maintaining a predetermined pressure of the underground pool of hot water, precludes the possibility of any great amount of this hot water escaping from the mine through underground strata, and at the same time insures a more uniform distribution of the heated water in the sulphur-bearing strata, thus accomplishing two important economies. It is possible by the careful regulation of the withdrawals of water from an old working, to carry on sulphur mining operations by means of fusion for long periods of time without the addition of any fresh heated water, thus allowing the power house to operate entirely on new deposits and at the same time keeping the old deposits in operation and producing sulphur.

It may be found advantageous in working a sulphur deposit according to the method of the present invention to increase slightly the temperature of the hot water withdrawn from the mine or to clarify this water by sedimentation or chemical treatment before reintroduction into the mine. Means for carrying out these operations have not been described or illustrated, but it is to be understood that such operations may be embodied in the system where desirable or necessary.

I claim:—

1. The improvement in the mining of sulphur by underground fusion from partially exhausted sulphur deposits, which comprises maintaining a predetermined pressure in the deposit by withdrawing water from the cold lower portion of the deposit and withdrawing hot water from the upper portion of the deposit and reintroducing the withdrawn hot water into the deposit.

2. The improvement in the mining of sulphur by underground fusion from partially exhausted sulphur deposits, which comprises maintaining a predetermined pressure in the deposit by pumping cold water from the lower portion of the deposit and withdrawing hot water from the upper portion of the deposit and reintroducing the withdrawn hot water into the deposit at a well zone remote from the zone of withdrawal of the hot water from the deposit.

3. The method of conserving hot water in the mining of sulphur by underground fusion from partially exhausted sulphur deposits, which comprises the balancing of underground pressures by regulated withdrawal of cold water from the lower portion of the deposit, regulated withdrawal of superheated water from the upper portion of the deposit, maintaining the withdrawn superheated water under pressure, and reintroducing the withdrawn superheated water into the deposit at a localized well zone.

4. The method of conserving hot water in the mining of sulphur by underground fusion from partially exhausted sulphur deposits, which comprises the balancing of un-

derground pressures by regulated withdrawal of cold water from the lower portion of the deposit, regulated withdrawal of superheated water from the upper portion of the deposit, maintaining the withdrawn superheated water under pressure, raising the temperature of the withdrawn superheated water, and reintroducing the resulting superheated water into the deposit at a localized well zone.

5. The method of conserving hot water in the mining of sulphur by underground fusion from partially exhausted sulphur deposits, which comprises sealing natural underground avenues of escape by means of mud pumped therein from the surface, thereafter balancing the underground pressure by regulated withdrawal of cold water from the lower portion of the deposit, regulated withdrawal of superheated water from the upper portion of the deposit, and maintaining the withdrawn superheated water under pressure and reintroducing it into the deposit at a localized well zone.

20 25 6. The improvement in the mining of sulphur by underground fusion from partially exhausted sulphur deposits, which comprises

balancing the rate of introduction of hot water into the deposit with the rate of withdrawal of water from the deposit in such manner as to build up and maintain a pressure within the deposit adapted to prevent the seepage of substantial amounts of hot water from the system.

7. The improvement in the mining of sulphur by underground fusion from partially exhausted sulphur deposits which comprises carefully regulating the rate of introduction of hot water into the deposit and the rate of withdrawal of cold water from the deposit so as to maintain a working pressure in the exhausted portion of the deposit at or near the normal hydrostatic pressure of the deposit.

8. The improvement in the mining of sulphur by underground fusion from partially exhausted sulphur deposits which comprises carefully regulating the rate of introduction of superheated liquid into the deposit and the rate of withdrawal of relatively cold liquid from the deposit so as to maintain a predetermined pressure of the hot liquid accumulating near the upper portion of the deposit.

In testimony whereof I affix my signature.
WILBER JUDSON.
